UNITED STATES PATENT OFFICE.

JOHN PFEIFER, OF SPRINGFIELD, OHIO.

DISK-HONER.

No. 908,129.

Specification of Letters Patent. Patented Dec. 29, 1908.

Application filed January 4, 1908. Serial No. 409,269.

To all whom it may concern:

Be it known that I, JOHN PFEIFER, a citizen of the United States, residing at Springfield, in the county of Clark and State of Ohio, have invented certain new and useful Improvements in Disk-Honers, of which the following is a specification.

My invention relates to improvements in honers and it particularly relates to a device of this kind especially adapted for honing disk cutting blades such as the ones now in common use in wall paper trimmers.

The object of my invention is to provide means for changing the position of the honing stones relatively to the blade during the operation of honing so as to prevent the honing surface of the same from becoming ridged or uneven.

A further object of my invention is to simplify, cheapen and make more effective the construction and operation of these devices.

My invention consists in the constructions and combinations of parts hereinafter described and set forth in the claims.

In the accompanying drawings, Figure 1 is a top plan view of a device embodying my improvements, considering that in the operation of the device the operator will grasp the handle with his left hand and operate the crank with his right, holding the device in a horizontal position; Fig. 2 is a side elevation of the crank side of the same; Fig. 3 is an end view of the device showing the honing stones in one extreme position of their movement; Fig. 4 is also an end view showing the honing stones in the other extreme position of their movement; Fig. 5 is a view of that side opposite the one on which the crank is located, the blade being partly broken away.

Like parts are represented by similar characters of reference in the several views.

In the said drawings, a a^1 a^2 , represent the main frame, preferably formed of U-shape, and having at one end thereof on the part, a , a suitable handle a^3 to be grasped by the operator. Journaled in the opposite ends of the frame parts, a^1 a^2 , is a main shaft, b , having secured at one end an operating crank, b^1 , and also having rigidly attached thereto, at a point between the two side members of the frame, a cam b^2 . This shaft is preferably capable of a longitudinal movement in the

bearings of said frame, this movement being limited by the crank in one direction and by the cam in the other, so as to permit the parts to adjust themselves with reference to each other more readily.

Journaled in the frame part a^1 and in an extension a^4 , extending upwardly from the frame part a^2 , is a rock shaft c , this rock shaft being extended in an angular direction as shown in Figs. 3 and 4. Connected to said rock shaft and extending upwardly about the cam b^2 is a forked piece or yoke c^1 , this forked piece or yoke being connected to said rock shaft through the medium of a set screw, c^2 , extending through the hub c^3 thereof to permit the yoke to be adjusted on said rock shaft. Connected to the outer end of said rock shaft is an upwardly extending arm c^4 , carrying at its outer end a honing stone c^5 . This rock shaft is also capable of longitudinal movement in its bearings in the frame parts and is normally spring pressed toward the right hand side of the device by a coil spring c^6 located between the frame extension a^4 and the hub of the yoke c^1 , the shaft being limited in its movement by the contact of said yoke or its hub, with the frame part a^1 . Also located in extensions a^5 and a^6 of the main frame is a rock shaft d . These frame extensions are located in a slightly angular position with reference to the main frame so that the rock shaft will extend in a slightly angular direction but not so great as the angle of the other rock shaft c . This rock shaft d , also carries a forked piece or yoke d^1 , secured to said shaft by a set screw d^2 in its hub d^3 which yoke or fork also straddles the said cam b^2 . This rock shaft also has at its outer or left hand end an upwardly extending arm d^4 , which carries at its upper end a honing stone d^5 . The rock shaft d is also capable of a limited movement in its bearings and has located thereon between the frame extension a^5 and the yoke d^1 or its hub a coil spring d^6 adapted to normally press the same in a direction toward the left of the machine or in a direction opposite to that in which the shaft c is pressed.

The disk cutting blade e , to be honed is secured to the end of the shaft, b , by the screw e^1 , and the adjustment and location

of the honers is such that they will be spring pressed against the outer edge of the said cutting disk on opposite sides thereof. In the device which I have illustrated in the drawings, the disk will be placed upon the shaft with its beveled edge out so that the honer, c^5 , which has the greatest angular position, will contact this beveled edge. The other honer d^4 , whose angular position is less than the one c^5 , will contact the inner or straight edge of the disk. The adjustment of the honing stone is also such that the outer ends of the stone will run off of the edge of the disk in one extreme of their movement, the stone d^5 in Fig. 3, and the stone c^5 in Fig. 4 illustrating this.

It will now be seen that as the shaft b is rotated by its crank, the cam, b^2 , will 20 through the medium of the respective yokes or forked pieces, $c^1 d^1$, cause the rock shafts c and d to be rocked back and forth, carrying with them the respective honers c^5 and d^5 across the cutting edge of the disk, so 25 that the entire surface of each honing stone from its outer end to a point near its inner end will be utilized in the honing action, thus preventing a ridge or groove from forming on the outer end of the stone which 30 would tend to dull the edge of the disk.

Having thus described my invention, I claim:

1. In a honing device, a support for the article to be honed, a honer located adjacent 35 to the plane occupied by the edge of said article, means for bringing said honer into contact with the edge of said article about the entire periphery thereof, and means for rotating said article and reciprocating said honer, substantially as specified.

2. In a honing device, a support for the article to be honed, honers located adjacent to the plane occupied by said article and on opposite sides thereof, means for bringing 45 said honers in contact with the edge of said article about the entire periphery thereof, and means for rotating said article and reciprocating said honers, substantially as and for the purpose specified.

50 3. In a honing device, means for supporting and rotating the article to be honed, a spring-pressed honer located adjacent to the plane occupied by the edge of said article, and means for reciprocating said honer, substantially as specified.

4. In a honing device of the character described, means for supporting and rotating the article to be honed, a spring-pressed honer located on each side of and adjacent 60 to the plane occupied by the edge of said article, and means for reciprocating said honers as the article is rotated, substantially as specified.

5. In a honing device, a rotatable shaft, means for securing the article to be honed to 65 said shaft, a honer located adjacent to the plane occupied by the edge of said article, and means operated by said shaft for reciprocating said honer, substantially as and for the purpose specified.

6. In a honing device of the character described, a rotatable shaft, means for securing the article to be honed to said shaft, a honer located on each side of the plane occupied by the edge of said article, and means operated 75 by said shaft for reciprocating said honers, substantially as specified.

7. In a honing device, a rotatable shaft, means for securing the article to be honed on 80 said shaft, a rock-shaft, a honer on said rock-shaft extending in proximity to the plane occupied by the edge of said article, and means operated by said rotatable shaft for rocking said rock-shaft, substantially as specified.

8. In a honing device, a rotatable main shaft, means for securing the article to be honed thereon, two rock-shafts, a honer supported by each of said rock-shafts in proximity to the plane occupied by the edge of 90 said article and on opposite sides thereof, means for holding said honers yieldingly against the edge of said article, and means operated by said main shaft for rocking said rock-shafts, substantially as specified.

9. In a honing device, a main rotatable shaft, means for supporting the article to be honed thereon, a rock-shaft, a honer connected to said rock-shaft extending in proximity to the plane occupied by the edge of 100 said article, means for holding said honer yieldingly to said article, a cam on said main shaft, and a projection on said rock-shaft extending in proximity to said cam for rocking said rock-shaft, substantially as specified. 105

10. In a honing device, a main rotatable shaft, means for supporting the article to be honed thereon, two rock-shafts, a honer connected to each rock-shaft and extending in proximity to the plane occupied by the edge 110 of said article, said honers being yieldingly held toward said plane, a cam on said main shaft, and a projection on each of said rock-shafts extending in proximity to said cam to cause said rock-shafts to be rocked thereby, 115 substantially as specified.

11. In a honing device, a main rotatable shaft, means for securing the article to be honed thereto, a rock-shaft, a honer supported by said rock-shaft in proximity to the 120 plane occupied by the edge of said article, said honer being set in angular relation to said plane and held yieldingly therein, and means operated by said main shaft for rocking said rock-shaft, substantially as and for 125 the purpose specified.

12. In a device of the character described, a main rotatable shaft, means for supporting the article to be honed thereon, two rock-shafts, a honer connected to each of said rock-shafts and located in proximity to the plane occupied by the edge of said article and on opposite sides thereof and in angular relation thereto, and means operated by said rotatable

shaft for rocking said rock-shafts, substantially as specified.

In testimony whereof, I have hereunto set my hand this 28th day of December, 1907

JOHN PFEIFER.
